United States Patent Office

Des. 202,367
Patented Sept. 21, 1965

202,367

COOKING DEVICE

Austin E. Cox, Wadsworth, Ohio, assignor to Dominion Electric Corporation, a corporation of Ohio

Filed Mar. 29, 1965, Ser. No. 84,499

Term of patent 14 years

(Cl. D44—1)

FIG. 1

FIG. 2

FIG. 4

The essential features of the design are shown in full lines, it being understood that the rear not shown and the bottom not shown are substantially plain and unornamented.

I claim:

The ornamental design for a cooking device, substantially as shown and described.
